UNITED STATES PATENT OFFICE

2,690,716

ROTARY PUMP

Barrett H. McLaughlin, Whitinsville, Mass.

Application December 29, 1952, Serial No. 328,446

1 Claim. (Cl. 103--123)

1

The present invention relates to new and useful improvements in rotary pumps and compressors.

An object of the invention is to provide a double acting abutment pump which works on the principle of increasing a volume within the pump; trapping the liquid which has been pulled in; connecting the volume with a discharge; and decreasing that volume.

Another object is to provide a rotary pump of improved efficiency, which is simple and practical in construction, relatively inexpensive to manufacture, and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view;

Figure 2 is a sectional view taken on a line 2--2 of Figure 1;

Figure 3 is a sectional view taken on a line 3--3 of Figure 2;

Figure 4 is a sectional view of the pump housing with the end plate and impeller removed, and

Figure 5 is an enlarged sectional view of one of the abutments.

Referring now to the drawings in detail, wherein for the purpose of illustration I have disclosed a preferred embodiment of my invention, the numeral 5 designates a pump housing formed with a circular pump chamber 6 and provided with a removable end or cover plate 7 secured to the housing by studs or bolts 8.

An inlet port 9 is formed in the top of the housing having a substantially rectangular shaped throat 10 extending substantially the entire width of chamber 6 and positioned substantially tangentially with respect to the chamber and an outlet port 11 is formed at one side of the housing and is provided with a throat 12 shaped similar to and entering chamber 6 adjacent throat 10 and positioned radially with respect to chamber 6.

An abutment 13 is slidable in a pocket 14 formed in the housing between throats 10 and 12, the outer end of the pocket being closed by a cover plate 15 secured to the housing by bolts 16 and a pair of guide pins 17 project inwardly at the inner side of the cover plate into bores 18 in the outer end of the abutment and on which the abutment is slidable. Coil springs 19 are positioned in the bores 18 behind the pins to project the inner rounded end of the abutment in the

2

chamber 6 to block off throat 10 from throat 12.

A second abutment 20 is slidable in a pocket 21 at a substantially diametrically opposite side of chamber 6 from abutment 13 and the two abutments and pockets are of duplicate construction whereby the abutments are spring projected into the chamber 6 and at an acute rearwardly disposed angle with respect to the direction of rotation of an impeller 22 of elliptical shape rotating in the chamber and of a size to have its major axis equal to the internal diameter of the chamber. The abutments bear against substantially diametrically opposite sides of the impeller.

A drive shaft 23 is cast integrally at one flat side of the impeller and is journaled in a bushing 24 supported in a stuffing box 25 at one side of the housing while a stub shaft 26 is cast integrally at the other flat side of the impeller and is journaled in a bushing 27 in a bearing recess 23 in cover plate 7.

A pair of passages 29 and 30 are formed in the impeller and each extend transversely with respect to the axis thereof and are inclined in crossed relation with respect to each other and have their adjacent ends positioned at opposite sides of the apex of the lobes 31 and 32 of the impeller so that a clearance is at all times provided between the circular wall of the chamber and the ends of the passages and while the lobes 31 and 32 are in close working contact with the wall of the chamber to block one passage from the other.

The opposite ends of the passages 29 and 30 are flared to provide relatively wide slot-like throats 33 extending substantially the entire width of the impeller for the unrestricted flow of liquid into and out of the passages from and to the chamber.

The volume of fluid being pumped is always constant in the pump chamber while volumes between certain points within the chamber are always changing. As the impeller 22 moves clockwise, the apex of lobe 31 moves away from abutment 13 and towards abutment 20 and the opposite apex of lobe 32 moves away from abutment 20 and towards abutment 13 causing the areas behind the lobes 31 and 32 to increase and pulling fluid into chamber 6 behind the lobes and forcing fluid in advance of the lobe 31 from the chamber through passage 29 and out of outlet port 11, as shown by the arrows in Figure 2, and also forcing the fluid in advance of lobe 32 directly out of outlet port 11.

The abutments 13 and 20 separate chamber 6 into an inlet chamber 34 having direct communi-

cation with inlet port 9 and an exhaust or outlet chamber 35 having direct communication with outlet port 11, as shown by dotted lines in Figure 2, and passages 29 and 30 connect the inlet and outlet chambers to each other at all stages of the rotation of the impeller.

The shape of the impeller and the crossed arrangement of the passages 29 and 30 cause the pump chamber 6 to be twice filled and emptied with each complete revolution of the impeller.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

What is claimed as new is as follows:

A pump comprising a housing providing a circular pump chamber and provided with inlet and outlet ports adjacent each other, an elliptical impeller fitted in and rotatable in said pump chamber and having diametrically opposite end lobes in the major axis of the impeller, a pair of spring biased abutments slidably in said housing to project into said pump chamber at diametrically opposite sides of the chamber and slidably engage said impeller, one of said abutments being located between said adjacent ports, said lobes and abutments in one direction of ro-

5 tation of the impeller dividing the pump chamber into a pair of diametrically opposite fluid intake and a pair of diametrically opposite fluid discharge chambers communicating with said inlet and outlet ports respectively, said lobes in said direction of rotation of the impeller creating intake in the intake chamber behind said lobes and pressure in the discharge chamber in front of said lobes to fill said intake chamber 10 and empty said discharge chamber through said inlet and outlet ports, respectively, and a pair of through passages in said impeller at opposite sides thereof crossed relatively to each other open at the ends thereof onto said lobes at diametrically opposite sides of the major axis of the impeller to cross connect said intake chambers behind said lobes and to cross connect said discharge chambers in front of said lobes, whereby 15 said pump chamber is filled and emptied twice 20 during each rotation of said impeller.
